UNITED STATES PATENT OFFICE

2,603,169

FLOOR RACK

Emmett C. Jahn, Chicago, Ill., assignor to Union Railway Equipment Company, Chicago, Ill., a corporation of South Dakota

Application January 24, 1950, Serial No. 140,313

3 Claims. (Cl. 105—375)

1

My invention relates to floor racks for railway cars and more particularly to that type which is employed in refrigerator cars to sustain the lading for cooling or warming by the circulating medium of the car.

It is one object of my invention to provide an all-metallic floor rack which constitutes a permanent fixture in the car, which can be readily cleaned and which is preferably made in individual sections that are hinged to and foldable against the side of the car to facilitate cleaning of the latter.

A further object is to provide a rack composed of sheet metal stringers and slats having specially designed sections to obtain maximum strength with lightness of weight and which are appropriately perforated and spaced to obtain free circulation of the car atmosphere.

A further object is to provide a rack which is reinforced in such a manner that the height of the rack can be reduced relative to existing racks to thereby increase the loading capacity of the car.

A further object is to provide for floor racks simple and inexpensive hinge constructions that are characterized by ample strength to withstand the severities of freight service.

These and further objects of the invention will be set forth in the following specification, reference being had to the accompanying drawings, and the novel means by which said objects are effectuated will be definitely pointed out in the claims.

In the drawings:

Fig. 1 is a diagrammatic, transverse, sectional elevation of a typical refrigerator car equipped with overhead, icing bunkers showing the relation of my improved rack thereto and to the flues which extend downwardly along the side walls of the car.

Fig. 2 is a diagrammatic plan view of the floor of a refrigerator car, showing the general relation of the rack units, including those opposite the door opening.

Fig. 3 is an enlarged view, partly in section, showing the lower left hand corner of the car and rack as viewed in Fig. 1, and illustrating the relation of the side wall flue to the spaces between the floor stringers which lie transversely of the car floor and the openings in the stringers which provide communication between these spaces.

Fig. 4 is a section along the line 4—4 in Fig. 5.

Fig. 5 is an enlarged plan view of one of the

2

racks looking in the direction of the arrow 5 in Fig. 4, the hinges being omitted.

Figs. 6 and 7 are enlarged, sectional elevations of the rack taken along the lines 6—6 and 7—7 in Figs. 3 and 6, respectively.

Fig. 8 is a side elevation of one of the floor stringers.

Fig. 9 is an enlarged, sectional elevation showing the hinge construction for those rack units which are pivoted to the lining of the car.

Fig. 10 is an enlarged section along the line 10—10 in Fig. 2 showing the hinge structure for the door rack units.

Fig. 11 is a section along the line 11—11 in Fig. 10.

Referring to Fig. 1, the numeral 10 designates a transverse section of a refrigerator car equipped with overhead icing baskets 11 and side wall flues 12 which conduct the cool air downwardly beneath the floor rack units 13 that sustain a lading 14.

A plurality of rack units 15 rest on the car floor between the ends of the car and the door openings 16 in adjacent and symmetrical relation on opposite sides of the longitudinal center line of the car, but with sufficient clearance between the several units so that they may be freely moved independently of each other. Each unit 15 is connected to the inside lining 17 by hinges generally indicated by the numeral 18 in Fig. 2. Opposite the door opening 16 and on both sides of the car center line is a pair of door rack units 19, each of which is connected to an adjacent unit 15 by hinges generally indicated by the numeral 20.

As indicated in Figs. 3, 4 and 6, each rack 15 comprises a plurality of floor stringers 21 which extend transversely of the car, the bottom of each stringer tapering gradually from the car center line towards the lining 17 for accommodation to the floor which is sloped for drainage, but the tops of the stringers are horizontal. The stringer 21 is formed as an open top channel having a base web 22 which rests on the floor 23 of the car and upwardly and outwardly extending side walls 24 whose upper edges are outwardly flanged as at 25. The stringers are spaced lengthwise of the car to define air ducts 26 which communicate with the flues 12 and with each other through openings 27 in the side walls 24.

As shown in Fig. 8, each stringer 21, except those which register with the hinges 18 as presently described, is slotted at 28 vertically downward from the top thereof for a predetermined distance, these slots being spaced along the length

of the stringer, one being spaced from each end and the remainder being arranged in two groups of two, the groups being spaced as are also the slots in each group. This arrangement is suggestive only.

The vertical leg 29 of an angle 30, constituting a slat stringer, is mounted in each slot 28 and welded to the side wall 24 with its horizontal leg 31 resting on the flanges 25. Accordingly, the angles or slat stringers are supported on and transversely disposed with reference to the floor stringers 21, i. e., the former extend longitudinally of the car and for the length of the associated rack unit. At the ends of the floor stringer, like slat stringers 32 have their vertical legs abutting and welded to the indicated ends with their horizontal legs resting on the flanges 25. The spacing of each slat stringer 32 from that slat stringer 30 which is mounted in the nearest slot 28 is equal to the spacing of the slat stringers 30 in the grouped slots 28. As illustrated in Figs. 3, 5 and 7, the facing edges of the horizontal legs of all the slat stringers are spaced from each other to facilitate circulation of air through the rack.

A plurality of spaced slats extend transversely of the car and are supported on the horizontal legs of the slat stringers 30 and 32. Each of the slats 33 is formed as in inverted channel having a supporting web 34 (see Fig. 6) on which the lading rests and downwardly and outwardly extending side walls or flanges 35 whose lower edges are outwardly reflanged above the slat stringers as at 36, the flanges 36 bearing on and being welded to the horizontal legs of the slat stringers 30 and 32 and the edges of adjacent flanges 36 abutting as indicated at 37 in Fig. 6. To strengthen the slats by increasing their vertical section between the slat stringers, the slat side walls 35 are continued below the horizontal legs of the slat stringers, as indicated by the numeral 38 in Figs. 3, 6 and 7.

Each slat 33 is provided with a longitudinal, open top duct 39 which is formed by offsetting the central portion of the web 34 and at spaced intervals along this duct, the bottom thereof is apertured at 40. Since the duct 39 is open ended, free circulation of the conditioning medium is assured therethrough, through the apertures 40, and through the openings 41 (see Fig. 5) between the downward extensions 38 of the slat side walls 35 which lie between the slat stringers 30.

The hinge connection 18 for each rack unit 15, referred to above, is more particularly illustrated in Fig. 9 to which reference will now be made. A pair of spaced brackets 42 are fastened to the inside lining at a convenient distance above the floor of the car, each bracket including spaced wings 43-43 between which is bridged a pin 44. Each bracket 42 is aligned with a floor stringer 21 and the side walls 24 of this particular floor stringer are cut away at 45 to accommodate the remainder of the hinge. A U-shaped strap 46 has its wings 47 and 48 welded to the vertical legs of the nearest slat stringers 30 and 32, respectively, and the wing 48 is extended upwardly around the pin 44 and downwardly to form the wing 49. The wings 48 and 49 are bridged by a bolt 50 and the ends of the adjacent slat 33 is cut away to clear the bracket 42. Those floor stringers 21 which are opposite the hinge brackets 42 are identical with the other floor stringers with the exception of the cut away portion 45 and the elimination of that slot 28 which is nearest the bracket 42. Hence, the rack units 15 may be swung to the dotted position shown in Fig. 3 and

secured by a suitable latch (not shown) when the car carries a lading which does not require the racks.

The door rack units 19 are constructed in the same manner as the racks 15 except that the former is smaller, the slat stringers being shorter and there being a smaller number of floor stringers and slats. The outermost floor stringer 21 of that rack 15 which is nearest the door has welded to its side wall 24 a vertical strap 51 (see Figs. 10 and 11) whose lower end is bent to form an eye 52 and a similar strap 53 having a like eye 54 is welded to the side wall of the adjacent floor stringer 55 of the door region floor rack 19. Pins 56 and 57 are journaled in the eyes 52 and 54, respectively, and the ends of the pins are connected by links 58-58. Accordingly, after the rack 15 adjacent the door opening has been swung to the dotted position shown in Fig. 3, the connected door region floor rack 19 may then be moved to lie inwardly of and against the rack 15 and secured in any approved manner.

Preferably, the stringers and slats are made of sheet metal of appropriate gauge which is galvanized to prevent corrosion of the racks. Rigidity of the rack as a whole is insured by the method of securing the stringers and slats together and by abutting the edges of the flanges 36 of adjacent slats, as clearly illustrated in Fig. 6. Moreover, the provision of tapering the side walls of the slats and floor stringers, as well as extending the side walls of the slats below the slat stringers, provides for the required strength of these elements of the racks, while at the same time permitting the use of a relatively light gauge metal. Further, the slotting of the floor stringers to receive the slat stringers not only laterally strengthens the floor stringers, but lowers the overall height of the rack and thus increases the lading capacity of the car.

Due to its rigid construction and strength, my improved rack is capable of withstanding buffing and switching shocks while loaded so that complete air circulation in the car is assured during transit.

I claim:

1. A floor rack for a refrigerator car for supporting a lading in spaced relation to the car floor to provide a flue therebetween comprising a plurality of spaced, channel, floor stringers, each stringer having flanges extending laterally from the upwardly projecting side walls thereof and a plurality of slots arranged in related, spaced pairs extending downwardly from the top of the floor stringer and terminating short of the bottom thereof, a plurality of angle slat stringers arranged in related spaced pairs disposed transversely of and secured to the floor stringers, one leg of each slat stringer fitting in one of the slots and the other leg resting on the floor stringer flanges, and a plurality of spaced, inverted channel slats disposed transversely of the slat stringers and having laterally extending flanges resting on and secured to said other slat stringer legs.

2. A floor rack for a refrigerator car for supporting a lading in spaced relation to the car floor to provide a flue therebetween comprising a plurality of spaced, channel, floor stringers, each stringer having flanges extending laterally from the upwardly projecting side walls thereof and a plurality of slots arranged in related, spaced pairs extending downwardly from the top of the floor stringer and terminating short of the bottom thereof, a plurality of angle slat stringers ar-

ranged in related spaced pairs disposed transversely of and secured to the floor stringers, one leg of each slat stringer fitting in one of the slots and the other leg resting on the floor stringer flanges, and a plurality of spaced, inverted, channel slats disposed transversely of the slat stringers, the side walls of each slat extending downwardly below the uppermost parts of and between the slat stringers to increase and vertically strengthen the slat section, the portions of each slat above the slat stringers having a reduced vertical section created by flanging the slat side walls for attachment to said other slat stringer legs.

3. A floor rack for a refrigerator car for supporting a lading in spaced relation to the car floor to provide a flue therebetween comprising a plurality of spaced, channel, floor stringers, each stringer having flanges extending laterally from the upwardly projecting side walls thereof and a plurality of slots arranged in related, spaced pairs extending downwardly from the top of the floor stringer and terminating short of the bottom thereof, a plurality of angle slat stringers arranged in related, spaced pairs disposed transversely of and secured to the floor stringers, one

leg of each slat stringer fitting in one of the slots and the other leg resting on the floor stringer flanges, and a plurality of spaced, inverted, channel slats disposed transversely of the slat stringers, the side walls of each slat extending downwardly below the uppermost parts of and between the slat stringers to increase and vertically strengthen the slat section, the portions of each slat above the slat stringers having a reduced vertical section created by reflanges on the slat side walls which rest upon and are secured to said other slat stringers legs in abutting relation only substantially above the slat stringers with the reflanges of the adjacent slats.
